Primary Examiner — Barbara Fox**CLAIM**

I claim the ornamental design for a computer, substantially as shown and described.

DESCRIPTION

FIG. 1 is a rear perspective view of a computer in accordance with the present design;

FIG. 2 is a front view thereof;

FIG. 3 is a rear view thereof;

FIG. 4 is a right side view thereof;

FIG. 5 is a left side view thereof; and,

FIG. 6 is another rear, perspective view thereof while the computer is in an upright position.

The broken lines shown in the drawings are for the purpose of illustrating unclaimed portions of the computer and form no part of the claimed design.
